UNITED STATES PATENT OFFICE

111,307

DESIGN FOR A DRESS

Jacob J. Kushner, New York, N. Y.

Application August 11, 1938, Serial No. 79,233

Term of patent 3½ years

To all whom it may concern:

Be it known that I, Jacob J. Kushner, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged side view of the sleeve showing the embroidery.

Fig. 4 is an enlarged fragmentary view of the collar portion of the dress.

I claim:

The ornamental design for a dress, substantially as shown.

JACOB J. KUSHNER.
